CLAIM

We claim the ornamental design for a helmet with an internal sunshield, as shown and described.

DESCRIPTION

FIG. 1. is a top front perspective view of a helmet with an internal sunshield of the present invention;

FIG. 2 is a top rear perspective view thereof;

FIG. 3 is a bottom front perspective view thereof;

FIG. 4 is a bottom rear perspective view thereof;

FIG. 5 is a front view thereof;

FIG. 6 is a rear view thereof;

FIG. 7 is a left view thereof;

FIG. 8 is a right view thereof;

FIG. 9 is a top view thereof;

FIG. 10 is a bottom view thereof;

FIG. 11 is a top front perspective view of a helmet with an internal sunshield showing the outer face shield in a raised position for clarity of illustration;

FIG. 12 is a top rear perspective view thereof;

FIG. 13 is a bottom front perspective view thereof;

FIG. 14 is a bottom rear perspective view thereof;

FIG. 15 is a front view thereof;

FIG. 16 is a rear view thereof;

FIG. 17 is a left view thereof;

FIG. 18 is a right view thereof;

FIG. 19 is a top view thereof;

FIG. 20 is a bottom view thereof;

FIG. 21 is a top front perspective view of a helmet with an internal sunshield showing the internal sunshield in a raised position for clarity of illustration;

FIG. 22 is a top rear right perspective view thereof;

FIG. 23 is a bottom front perspective view thereof;

FIG. 24 is a bottom rear perspective view thereof;

FIG. 25 is a front view thereof;

FIG. 26 is a rear view thereof;

FIG. 27 is a left view thereof;

FIG. 28 is a right view thereof;

FIG. 29 is a top view thereof; and,

FIG. 30 is a bottom view thereof.
